Primary Examiner — Wan Laymon(57) **CLAIM**

The ornamental design for a light source device for projector, as shown and described.

DESCRIPTION

FIG. 1 is a front, top and right side perspective view of a light source device for projector showing our new design; FIG. 2 is a front, top and left side perspective view thereof; FIG. 3 is a perspective view of a duct member, separately shown for clarity of illustration; and, FIG. 4 is a rear, top and right side perspective view of a light source device for projector.

The features shown in broken lines in the drawings depict environmental subject matter only and form no part of the claimed design.
